PORTABLE OIL HEATER

Julius H. Hupfer, Glastonbury, Conn., assignor to
 Bunsen Incorporated of Hartford, Conn., a
 corporation of Connecticut

Application October 11, 1940, Serial No. 360,783

5 Claims. (Cl. 126—96)

The invention relates to portable oil burning heaters of the distillate type which are especially adapted for keeping warm the motors of automobiles and airplanes when stored in unheated garages or parked in the open in localities subject to low temperatures, so that the cooling liquids will not freeze, the lubricants will not solidify, and the motors will start without delay.

The object of the invention is to provide a small, inexpensive portable heater which will utilize common readily procured fuel, and that is easily lighted, starts burning quickly, generates high heat, is safe from explosion and free from liability of being extinguished even by strong drafts when once lighted.

In the accompanying drawing Fig. 1 shows on reduced scale, a side elevation with part of the snuffing cylinder broken away, of a heater that embodies the invention.

Fig. 2 shows on larger scale, a vertical section on plane denoted by dotted line 2—2 on Fig. 1.

Fig. 3 is a horizontal section looking down on plane denoted by dotted line 3—3 on Fig. 2.

Fig. 4 is a horizontal section on plane denoted by dotted line 4—4 on Fig. 2, with the starting wick and snuffing cylinder omitted.

The heater has a reservoir 1, preferably of metal, for containing the heating fuel which may be ordinary kerosene. The reservoir may have a handle 2, and a filling cap 3 with a small orifice 4 to permit the entrance of air as the fuel is consumed. Around a central opening through the top of the reservoir is an upwardly projecting wall 5 and encircling this wall and bounded on the outside by a wall 6 is a channel 7. This channel is designed to receive a small quantity of readily combustible fuel such as alcohol, which when ignited will generate heat for producing an initial vaporization of the heating fuel and for lighting the burner. The channel 7 desirably contains a wick 8.

Set into the wall 5 below its upper edge is a burner head which consists of a disk 9 that has an upwardly extending flange 10 around a central opening and an upwardly extending flange 11 that encircles and is spaced from the flange 10. The disk 9 rests on a ledge 12 formed around the inside of the wall 5 and is desirably retained in place by a spring ring 13. The disk 9 has a plurality of perforations 14 between the flanges 10 and 11 and also a plurality of perforations 15 outside of the flange 11, and extending across the under face of the disk is a fine mesh wire screen 16.

A tube 17 passes through the center of the

disk and a wick 18, woven of the usual absorbent material in the shape of a solid cylinder, is arranged to extend through the tube from slightly below the upper end of the tube into the reservoir.

Fitted upon and extending upwardly from the wall 5 that extends upward from the reservoir is a relatively short perforated metal cylindrical shell 19. Fitted to the flange 11 that extends upward from the burner head is a relatively short perforated metal shell 20. The perforations through these shells are substantially the same diameter. The upper end of the shell 20 is tightly closed by a plate 21 which is shown as having outwardly extending fingers 22 that engage against the outer shell 19 and center the upper end of the shell 20 without practical interference with the upward flow of air and gases between the shells 19 and 20. The space 23 in the inner shell functions as a vaporizing chamber and the space 24 between the shells functions as a combustion chamber when the heater is in use.

From the center of the plate 21 which closes the top of the inner shell is an upwardly extending spindle 25 that at its upper end has a perforated metal dispersion disk 26 of substantially the same diameter as the diameter of the outer shell. A cylindrical fine mesh wire safety screen 27 with its vertical wall protected by a metal grill 28 is placed over the burner with its lower end closely fitted within and attached to the wall 6 that extends around the ignition channel 7 by a common bayonet joint 29.

Over and enclosing the screen is a removable cup-shaped snuffing cylinder 30. The side and top walls of this cylinder are closed and the lower open end loosely rests upon the edge of the wall 6. Perforated lugs 31 project outward from the wall 6 for the purpose of receiving the ends of a bail 32 by which the heater may be hung under the hood from any convenient bar or other projection of an automobile or other motor in position to keep the motor warm.

To use the heater described the snuffing cylinder is removed and set one side, the reservoir supplied with fuel, usually kerosene, the screen slightly raised and a small quantity of ignition fluid, such as alcohol, is injected into the channel 7 at the top of the reservoir around the outside of the burner head and ignited. As soon as the ignition fluid is lighted the screen is lowered into place. The burning of the ignition fluid continues only long enough to heat the burner head and cause a volatilization of the heating fuel in the inner shell, or vaporizing chamber 23, and

ignite the vapor which escapes from the vaporizing chamber to the combustion chamber 24 or space between the two perforated shells. The small quantity of ignition fuel is soon exhausted and the burner continues to function with a hot flame in the combustion chamber. Air for supporting combustion and providing the proper mixture and drafts for generating a hot flame is drawn through the screen and through the perforations in the sleeves and burner head, and the resulting heat is spread throughout the entire interior of the screen by the dispersion disk 28. As air can enter through the screen but flame cannot pass from the interior to the exterior of the screen there is no liability of explosion or danger of accidental fire.

The perforations through the shells 19 and 20 permit of a draft across the wick which assists the capillary action of the wick so that the stronger the draft the greater the volume of fuel 20 drawn up and ignited, and yet the flame is so protected that it cannot be blown out or extinguished by any wind to which it may be exposed when in use.

Strong blasts of air blown through the screen 25 from any direction so circulate around in the space between the inner and outer shells that while on the side from which the blasts come the flame may be diverted it accumulates on the other side and keeps the heating fuel ignited. It has been demonstrated that the internal air drafts are in such direction and the flame burns with such intensity that drafts having a velocity of many miles per hour against the screen will not extinguish the flame, and it is only when the supply of oxygen is completely shut off by the application of the snuffer that the flame can usually be extinguished.

The combustion of fuel in this heater takes place in such a locality that the central wick does not become charred or burned sufficiently to render it inefficient for a long period of time, and when this happens the wick and the burner head are, as a unit, removed and discarded and another unit substituted.

The invention claimed is:

1. A heater which comprises a reservoir with a central opening through the top, a burner head with annularly positioned perforations located in said reservoir opening, a wick tube with an imperforate side wall supported by and extending through said head, a cylindrical shell larger in diameter than the wick tube supported by said head and extending upward higher than the wick tube, said shell having a perforated side wall, a closed upper end and an open lower end encircling a portion of the annularly positioned perforations through said head and providing a vaporizing chamber above the wick tube, a cylindrical shell larger in diameter than, spaced from and encircling the vaporizing chamber shell and extending upward higher than the wick tube, said larger shell having a perforated side wall, an open upper end and an open bottom end encircling a portion of the annularly positioned perforations through said head and providing a combustion chamber that is open at top and bottom about the vaporizing chamber, a fine mesh screen resting upon the top of the reservoir, spaced from and enclosing said shells and burner head, and a metal grill surrounding said screen.

2. A heater which comprises a reservoir with a central opening through the top, a burner head with annularly positioned perforations located

in said reservoir opening, a wick tube with an imperforate side wall supported by and extending through said head, a cylindrical shell larger in diameter than the wick tube supported by said head and extending upward higher than the wick tube, said shell having a perforated side wall, a closed upper end and an open lower end encircling a portion of the annularly positioned perforations through said head and providing a vaporizing chamber above the wick tube, a cylindrical shell larger in diameter than, spaced from and encircling the vaporizing chamber shell and extending upward higher than the wick tube, said larger shell having a perforated side wall, an open upper end and an open bottom end encircling a portion of the annularly positioned perforations through said head and providing a combustion chamber that is open at top and bottom about the vaporizing chamber, an annular ignition channel surrounding and spaced from the shell that forms the outer wall of the combustion chamber, a fine mesh screen resting upon the top of the reservoir, spaced from and enclosing said shells, burner head and ignition channel, and a metal grill surrounding said screen.

3. A heater which comprises a reservoir with a central opening through the top, a disk with annularly positioned perforations loosely located in said reservoir opening, a wick tube with an imperforate side wall extending through and loosely supported by said disk, a cylindrical shell larger in diameter than the wick tube supported by said disk and extending upward higher than the wick tube, said shell having a perforated side wall, a closed upper end and an open lower end encircling a portion of the annularly positioned perforations through said disk and providing an enlarged vaporizing chamber above the wick tube, a cylindrical shell larger in diameter than, spaced from and encircling the vaporizing chamber shell, and extending upward higher than the wick tube, said larger shell having a perforated side wall, an open upper end and an open bottom end encircling a portion of the annularly positioned perforations through said disk and providing a combustion chamber that is open at top and bottom about the vaporizing chamber, a fine mesh screen resting upon the top of the reservoir, spaced from and enclosing said shells and a metal grill encircling said screen.

4. A heater which comprises a reservoir with a central opening through the top, a disk with annularly positioned perforations and an upwardly extending flange loosely located in said reservoir opening, a wick tube with an imperforate side wall extending through and supported by said disk flange, a cylindrical shell larger in diameter than the wick tube supported by said disk and extending upward higher than the wick tube, said shell having a perforated side wall, a closed upper end and an open lower end encircling a portion of the annularly positioned perforations through said disk and providing an enlarged vaporizing chamber above the wick tube, a cylindrical shell larger in diameter than, spaced from and encircling the vaporizing chamber shell and extending upward higher than the wick tube, said larger shell having a perforated side wall, an open upper end and an open bottom end encircling a portion of the annularly positioned perforations through said disk and providing a combustion chamber that is open at top and bottom about the vaporizing chamber, a perforated dispersion disk of substantially the same dia-

ter as that of the outer shell supported by and spaced from the closed top of the inner shell, a fine mesh screen resting upon the top of the reservoir, spaced from and enclosing said shells and disk, and a metal grill encircling said screen.

5. A heater adapted to be used where it will be subjected to strong blasts of wind, which comprises a reservoir for containing readily vaporized liquid fuel, said reservoir having a closed bottom and side wall and a central opening through its top, a burner head located in said reservoir opening, said head having inner and outer annular rows of perforations that communicate with the interior of the reservoir, a wick tube having an imperforate side wall extending through the center of said head, said tube being less in diameter than the diameter of the inner row of said perforations through the head, a wick extending

upward from the reservoir within the wick tube, a cylindrical vaporizing chamber that is larger in diameter than and that extends upward higher than the wick tube, said vaporizing chamber 5 having a perforated side wall, a closed upper end, and having its lower end communicating with the reservoir through the inner annular row of perforations in the head, an annular combustion chamber that is larger in diameter than and encircles said vaporizing chamber, said combustion chamber having a perforated side wall, an open upper end and an open lower end that communicates with the reservoir through the outer annular row of perforations in the head, a fine mesh 10 screen enclosing said vaporizing and combustion chambers, and a metal grill encircling said screen.
